ANTHONY F. ZEGA, OF NEWARK, NEW JERSEY.

STOP FOR TALKING-MACHINES.

1,292,214.

Specification of Letters Patent. Patented Jan. 21, 1919.

Application filed February 5, 1917. Serial No. 146,554.

To all whom it may concern:

Be it known that I, ANTHONY F. ZEGA, a citizen of the United States, and a resident of Newark, county of Essex, and State of New Jersey, have invented certain new and useful Improvements in Stops for Talking-Machines, of which the following is a specification.

This invention relates to an improved stop for talking machines and is adapted to operate a brake when the reproduction is finished, the brake being operated through intermediate mechanism from the tone arm which is swung slowly by the pitch of the record groove in which the needle of the reproducer travels.

The invention is further designed to provide a stop of this kind by means of which the brake can be manually operated, that part of the mechanism that is operated from the tone arm and also that part that is operated manually being yieldingly held in locking or stopping position by a single spring.

The invention further consists in a stop mechanism in which the stud on the tone arm and the arm engaged by the stud, the engagement of which parts operates the brake to stop the record table, are arranged so that they can be adjusted relative to each other so that the point where the reproducer needle is on the record can be approximately fixed when said stud and arm come in contact. This adjustment is devised because on

ten and twelve inch records the average reproducing groove is a certain distance from the center of the record. On seven inch records and on six inch records the end of the groove is much closer to the center of the table and the tone arm is swung in further before the reproduction is finished, and the engagement of these operated parts must therefore be deferred on the smaller records.

The invention is further designed to provide a machine of this kind in which the ordinary record can be employed, but I also use a record in connection with this device in which the movement of the tone arm is accelerated when the reproduction is finished so that the tone arm is swung rather sharply toward the center of the record and a positive stopping at once results.

The invention is further designed to provide a stop of the kind above described which is somewhat sensitive and easily oper-

ated and is practically noiseless, since it is accompanied by no unpleasant clicks or thuds incidental to its operation.

The invention is illustrated in the accompanying drawings, in which Figure 1 is a top view of the device and also illustrating enough of the phonograph case to indicate the co-operation of the parts, and also illustrating a record provided with the grooves in extension of the record or reproducing groove to positively operate the stop actuating device when the reproduction is finished. Fig. 2 is a side view of the construction illustrated in Fig. 1, and Fig. 3 is a detail view showing a part of the stop mechanism shown in Fig. 1 with some of the parts broken away and with the spring removed to more clearly show the parts underneath. Fig. 4 is a section on line 4-4 in Fig. 1. Fig. 5 is a top view, and Fig. 6 is a side view of a modified form of stop mechanism. Fig. 7 is a top view of still another modification, and Fig. 8 is a side view of the device shown in Fig. 7. Fig. 9 is a section on line 9-9 in Fig. 7.

In the drawings 10 represents the phonograph case through the top of which projects the post 11 which is driven by a motor which is usual in machines of this kind and on which is mounted a table 12 which revolves with the post 11, the table 12 having a flange 13 (Fig. 5) which projects downward and against the inner face of which the brake operates. A tone arm 14 is mounted to swing in any usual way, the form shown employing a bracket 15 on which the large end of the tone arm swings, the end of the tone arm being provided with a reproducer 16 carrying a needle 17 which travels in a groove 18 on the top face of the record 19, the groove 18 being adapted to reproduce, through the needle 17, a reproduction which is transmitted to the tone arm and then out through a suitable amplifying device. The locking mechanism is preferably disposed beneath the record table and can be mounted directly thereon, but in order to insure smooth operation of the parts and to make a more unitary structure of it, I employ a base plate 20 which is fastened to the top cabinet 10 and has pivoted thereto a hub 21 which has a finger 22 fastened thereto, this finger being preferably struck up from the hub and it is provided with a brake 23, usually of vibrous material or felt so as to give a positive fric-

tional engagement of the flange 13 with the record table and to make such engagement noiseless. A handle 24 extends from the hub 21 and provides means by which it can be 5 manually operated to release or to set the brake 23. A tripping arm 25 is operated from the hub and for this purpose is preferably secured thereto as at 26 and is held in position and permitted to slide by suitable mechanism, the form illustrated comprising a pin 27 which is fastened to the base plate 20 and slides in a slot 28 in the tripping arm 25, the tripping arm having a projection 29 thereon and its end 30' being tapered. Slidably arranged on the base plate 20 is a slide member 30 which can be held in position by any suitable means, such as the pins 31, which project up through the slots 32 and are headed so as 10 to hold the slide in position, the slide having a recess 33 which is longer than the projection 29, thus allowing a little play for the projection of parts, which will be described hereinafter. On the end of the base plate 20 opposite the hub 21 is a detent 34 oscillating on a suitable pivot 35, the detent having the hub portion 36 through which the pin 35 passes. The detent 34 has a nose 37 which is adapted to fit into a recess 38, the 15 end of the detent 39 being tapered and being adapted to fit against the tapered end 30' of the tripping arm 35. An arm 40 has a hub through which the pin 35 passes, the arm when swung in one direction pulling the detent on its pivot, the parts being connected in any suitable way, in the form shown being connected by means of a screw 41 screw-threaded into a boss 42 struck up from the hub of the arm 40, the screw having its head 43 bearing against a boss 44 struck up from the detent, the boss 44 being preferably slotted as at 45 to give a little side motion to the screw so that the arm 40 can be moved in reverse direction 20 without bending or breaking any of the parts, but when moved forward to swing the detent it positively engages the detent, this screw adjustment being adapted to be permanently made when the stop mechanism 25 is installed in the machine and not necessarily altered unless it is to adapt it to a particular type of machine on which it is installed.

A spring 46 connects the detent and the 30 slide, such connection being preferably made by passing the ends of the spring over a pin 47 on the detent and a pin 48 on the slide. The arm 40 is adapted to be engaged by a stud fastened to the tone arm of the machine, and when the needle 17 reaches the 35 end of the reproduction and is traveling in the excess groove beyond the reproduction point, the records being provided with such excess groove, the stud on the tone arm, 40 which will be hereinafter described, engages

the arm 40 and swings it. The arm 40 acts to swing the detent 34 through the mechanism hereinbefore described. The detent when swung pulls the nose 37 from the recess 38, at the same time giving a little tension to the spring 46 which then positively pulls on the slide which in turn pulls on the tripping arm 25 which is free to be moved, since in the swinging of the detent the end 39 comes away from the end 30' of the tripping arm. The tripping arm when thus pulled by the slide, under the influence of the spring 46, swings the hub 21 and forces the brake 23 against the flange 13 of the record table and the record is stopped. 70 75 80

One form of attachment for the tone arm is illustrated in Figs. 1, 2 and 4, and comprises a bracket 49 preferably formed of sheet metal and riveted as at 50 to the tone arm, although other means of securing it 85 may be employed, the bracket being made of sheet metal and being bent to form bearings 51 and 52 and also to form a table 53 having stops 54 and 55 on it, the bearings acting to support a shaft 56, the shaft having on the top an index hand 57 with a handle 58 for operating it, the handle 58 having its bottom edge formed into a head 59 which fits into any of the several recesses 60 in the plate 53, the index hand 57 thus 90 being stopped when the head engages such recesses and being adapted to be manually lifted or slid therefrom when desired, but being held tight enough to prevent accidental movement of the index hand. The index hand is held down by means of a spring 61 which bears against the lower bearing 52 and also against an arm 63 which has a square hole fitting into a square end 64 of the shaft 56, the arm 63 carrying at its end a stud 65 which depends so that it engages the arm 40 to bring about the stopping motion above described. The ends of ten and twelve inch records, that is, the inner ends of the record grooves, are at approximately the same 95 point on all records, the six and seven inch records having the concluding or inner ends of their records much nearer the center of the record so that in the smaller records the engagement of the arm 40 by the stud 65 must be delayed, this being accomplished by 100 swinging the arm 63 by means of the handle 58, and in this way the stop is made in a sense universal, since it can be adapted for different forms of records without the necessity of previously moving the tone arm over to a position where the reproduction stops and then adjusting the stopping device to this position. When a ten inch record is put on, the index hand 57 is swung to indicate the point where the index on the table 53 indicates such record, and this swings the stud to a point where it will engage the arm 40 when the reproducer needle has moved the tone arm by reason of the end 105 110 115 120 125 130

of the reproduction part of the record having engaged the needle of the reproducer.

When the brake is to be manually operated the handle 24 is swung and the 5 tapered ends 30' and 39 act so as to swing the detent outward, the movement of the tripping arm incidental to the movement of the handle 24 being possible by reason of the recess 38 being longer than the projection 29, and when the detent has been moved out far enough the projection 47 leaves the recess 38, which is a comparatively shallow recess, and the spring 46 is again under a slight tension, the slide 30 10 moves longitudinally and the parts are in position to hold the brake 23 against the flange of the record table.

The device is reset by pulling back on the handle 24 which slides the tripping arm 20 which in turn causes the slide 30 to move, such movement of the slide giving a tension to the spring 46 which swings the detent into position, the projection 37 and the recess 38 coming together to lock the parts, 25 the brake is released and the record table is free to revolve.

In the modification shown in Figs. 5 and 6 the detent and the brake arm are the same as in the previously described figures, the 30 tripping arm 66, however, being without projection on its side and being mounted so as to be secured by the pin 67 so that it has no movement relative to the hub 21. The pin 67, however, instead of being positively 35 secured to the slide 68, works in a slot 69 in the slide so that when the hub 21 is swung by reason of the handle 24 being pushed from the position shown in Fig. 5, the tripping arm 66 is moved forward so that the 40 abutting edges 30' and 39, by reason of their being inclined, force the detent out, the latch remains stationary until the projection 37 is moved from the recess 38 and then the spring 70 snaps the slide 68 so as to bring 45 the end of the slot 69 against the pin 67 and the slide is then free to pull, under the influence of the spring 70, on the hub 21 to force the brake 23 against the turntable or record table.

50 In the modification shown in Figs. 7 and 8 the brake and the tripping arm and also the slide are similar to the constructions shown in Figs. 1 and 2, but there is a difference in the adjusting mechanism, as the detent 71 has a hub 72 (Figs. 8 and 9) which is between the hub 73 of the pointer 74 and the hub 75 of the arm 76. The arm 76 is adapted to be engaged by the stud 77 of the tone arm 14, which stud in this construction is fixed 55 in its relation to the tone arm. The hubs 72, 73 and 75 are arranged around the eyelet 78, the bottom ends of the eyelet being headed as at 79 and having an annular groove into which the edge of the slot 80 of a spring disk 60 or washer 81 fits. The eyelet is held in place

by a stud 82 which is fastened at its bottom, as at 83, to the base plate 20. The pointer arm 74 is connected by a screw 84 to the arm 76 and is provided on its outer end with a suitable handle 85 by means of which it is 70 operated, the pointer being adapted to register on a plate 86 which is suitably graduated and has a loop 87 struck up from it to hold the pointer arm 74 in place. When the pointer arm is swung to indicate the size of 75 the record with which the stop is to be used, it operates, by means of the friction disk 81, to swing the arm 76 with it, the pointer arm when being swung down having no effect on the detent 71 because the detent 71 bears 80 against the slide 30, and when it is moved upward, which is usually the case, that is, before the record begins to play, the detent rests against a stop 88, preferably struck up from the base plate 20. The spring 46 in 85 this construction performs the same function as in the construction shown in Figs. 1 and 2, that is, it tends to pull the slide, the tripping arm, and consequently the brake, when the detent is swung to a releasing position. 90

The average phonograph record has usually enough additional groove beyond where the reproduction stops to move the tone arm sufficiently to operate the brake, but in 95 order to be assured of such stopping, I prefer to use a record in which the groove is continued with a sharper curve toward the center of the record. Such record is shown in Fig. 1, the reproducing part of the groove 100 18 merging into a part 89 which is a continuation of the record groove but has a sharper spiral so that the tone arm is positively moved and thus accelerated in its movement toward the center of the record 105 and gives a decided and sharp push to the arm 40. A similar sharper spiral groove or grooves 90 can be installed at the plain edge of the groove, that is, on the space between where the record groove begins and the outer 110 edge of the record, so that there is no danger of the needle, after being placed on this smooth part, running off the edge of the record and thus scratching up the felt with which the turntables are usually covered and 115 making a discordant, rasping sound, and the needle is positively fed promptly and without failure into the record groove.

Having thus described my invention, I claim:

1. A stop for talking machines comprising a slide, a detent for the slide, a spring connecting the slide and the detent, an arm to operate the detent from the tone arm of the talking machine, a brake, a handle to operate 120 the brake, and a tripping arm connected to the handle and adapted to trip the detent and to have a limited sliding contact relative to the slide.

2. A stop for talking machines comprising 125 130

- 4 a slide, a detent for the slide, a spring connecting the slide and the detent, an arm to operate the detent from the tone arm of the talking machine, a brake, a handle to operate the brake, a tripping arm connected to the handle and adapted to trip the detent and to have a limited sliding contact relative to the slide, and means for relatively adjusting the means on the tone arm and the arm on the detent.
- 5 3. A stop for talking machines comprising a slide, a detent having an arm thereon and means for locking the slide, a trip having a brake thereon and provided with a handle 10 for its manual operation, coacting means on the slide and on the trip to permit a limited sliding contact between them, and a spring connecting the detent and the slide.
- 6 4. A stop for talking machines comprising a slide, a brake having a handle thereon, a tripping arm on the brake and having a connection with the slide, a detent having a connection with the slide and with the tripping arm, a spring connection between the 15 slide and the detent, whereby the handle can be operated to set the slide and also be operated to trip the detent, and an arm on the detent adapted to be operated by the tone arm of a talking machine.
- 7 5. A stop for talking machines comprising a spring actuated slide, a spring operated detent, an arm to operate the detent from the tone arm of a talking machine, a combined tripping and locking mechanism 20 adapted to engage both the slide and the detent, a brake connected to the combined tripping and locking mechanism, and a handle connected to the brake whereby the brake and the combined tripping and locking mechanism may be manually operated.
- 8 6. A stop for talking machines comprising a spring actuated slide, a spring operated detent, an arm to operate the detent from the tone arm of a talking machine, a combined tripping and locking mechanism 25 adapted to engage both the slide and the detent, a brake connected to the combined tripping and locking mechanism, and means for shifting the point of contact at which the 30 arm on the detent and the arm on the tone arm come in contact to release the detent, said means including a pointer arm, and an indicator whereby said point of contact can be selected.
- 9 7. A stop for talking machines comprising a hub having a brake and a handle thereon, a swinging detent arm, a detent secured to the hub, which detent is swung with the detent arm, a slide having means co-acting 35 with the detent arm for locking the slide against sliding movement, and a tripping arm having a limited sliding contact relative to the slide, the tripping arm and the de?
- 10 tent having their abutting ends constructed so that when the handle of the brake is 65 swung the tripping arm swings the detent.
- 11 8. A stop for talking machines comprising a spring actuated slide, a brake having a handle thereon for its manual operation, a detent, a tripping arm connected to the brake 70 and having its end adapted to abut on the end of the detent, said abutting ends being tapered, co-acting means on the slide and the detent to prevent the slide from moving when engaged by the detent, co-acting means 75 on the slide and the tripping arm and permitting a limited sliding movement relative to one another, an arm on the detent, and means on the tone arm of a talking machine for engaging the arm on the detent. 80
- 12 9. A stop for talking machines comprising a spring actuated slide, a brake having a handle thereon for its manual operation, a detent, a tripping arm connected to the brake 85 and having its end adapted to abut on the end of the detent, said abutting ends being tapered, co-acting means on the slide and the detent to prevent the slide from moving when engaged by the detent, co-acting means 90 on the slide and the tripping arm and permitting a limited sliding movement relative to one another, an arm on the detent, means on the tone arm of a talking machine for 95 engaging the arm on the detent, and a selective contact between the arm on the detent and the means on the tone arm.
- 13 10. A stop for talking machines comprising a spring actuated slide, a brake having a handle thereon for its manual operation, 100 a detent, a tripping arm connected to the brake and having its end adapted to abut on the end of the detent, said abutting ends being tapered, co-acting means on the slide 105 and the detent to prevent the slide from moving when engaged by the detent, co-acting means on the slide and the tripping arm and permitting a limited sliding movement relative to one another, an arm on the detent, means on the tone arm of a talking machine 110 for engaging the arm on the detent, means for changing the point of contact between the arm on the detent and the means on the tone arm, said means embracing a pointer, a scale on which said pointer operates for indicating said point of contact, a handle on 115 said pointer, and means for holding the pointer in predetermined positions, said means resisting displacement in the operation of the lock but yielding to manual operation. 120
- 14 In testimony that I claim the foregoing, I hereto set my hand, this 30th day of January, 1917.
- ANTONEY F. ZEGA.
